UNITED STATES PATENT OFFICE.

HAROLD L. BLOOD, OF PLAINFIELD, NEW JERSEY, ASSIGNOR TO NILES-BEMENT-POND COMPANY, OF NEW YORK, N. Y., A CORPORATION OF NEW JERSEY.

SWITCH MECHANISM.

Original application filed January 31, 1920, Serial No. 355,318. Divided and this application filed May 11, 1921. Serial No. 468,576.

To all whom it may concern:

Be it known that I, HAROLD L. BLOOD, a citizen of the United States, residing at Plainfield, in the county of Union and State 5 of New Jersey, have invented certain new and useful Improvements in Switch Mechanism, of which the following is a specification.

My invention relates to switch mechanisms and particularly to switch mechanisms 10 for controlling the operation of electric motors.

One object of my invention is to provide a switch mechanism that shall embody a pivotally mounted switch lever operating two sets of contact members, a main magnet for operating the switch lever and a supplemental magnet which not only serves to oppose the main magnet but also serves as a 20 blow-out magnet to extinguish the arcs formed by certain of the contact members.

Another object of my invention is to provide a switch mechanism having pivotally mounted switch levers and contact members 25 that shall be controlled by oppositely acting main and supplemental magnets in a simple and in an efficient manner, that shall extinguish arcs, which are formed by certain of the contact members, by means of the supplemental magnets and that shall interlock the main magnets to prevent operation of the levers under certain conditions.

More specifically, my invention comprises 30 a switch mechanism embodying three pivotally mounted switch levers having contact members on their oposite ends and co-acting with stationary contact members, one only of said movable contact members being insulated from the switch lever carrying it, a 35 main magnet for operating each of the switch levers, supplemental magnets associated with two of said levers and serving not only to oppose the main magnets but also to extinguish the arcs formed by cer- 40 tain of the contact members, and interlock switches operated by the supplemental magnets and included in the energizing circuit of certain of the main magnets.

In providing a switch mechanism for controlling electric motors, it is desirable and 45 in some cases essential to provide a mechanism embodying few parts not only to render it relatively inexpensive to construct but

also to occupy a minimum of space. The described switch mechanism occupies a limited 55 space and is adapted to control the operation of a motor in a forward and in a reversed direction and to complete a dynamic braking circuit.

This application is a division of my co- 60 pending application for planers and systems of motor control therefor, Serial No. 355,318, filed January 31st, 1920.

In the accompanying drawing:

Figure 1 is a front elevational view of the 65 switch mechanism, the major portion of the cover being broken away to show the interior parts.

Fig. 2 is a perspective view of one of the 70 supporting brackets shown in Fig. 1.

Fig. 3 is a vertical sectional view of the 75 control switch mechanism taken along the line 3—3 of Fig. 1.

Fig. 4 is a vertical sectional view of the switch mechanism taken along the line 4—4 75 of Fig. 1.

Fig. 5 is a vertical sectional view of the switch mechanism taken along the line 5—5 of Fig. 1.

Fig. 6 is a fragmentary side elevational 80 view of a planer adapted to be operated by a switch mechanism constructed in accordance with my invention.

Fig. 7 is a diagrammatic view of the electrical connections in a system controlled by 85 my switch mechanism.

Referring to the accompanying drawings and particularly to Figs. 6 and 7, I have shown my switch mechanism in a system for controlling the operation of a planer. Only 90 a brief description will be given of the planer and of the control system, inasmuch as my invention relates particularly to the switch mechanism and to the circuits for energizing the electro-magnets of such mech- 95 anism.

The planer, which is diagrammatically shown in Fig. 6 of the drawings, comprises a work carrying table 1 which is mounted on a bed 2. A motor 3, which is connected to the table 1 by means of any suitable gearing 4, is provided for effecting reciprocal movements of the table. The motor 3 is controlled by a pilot switch 5 which in turn is controlled by the planer table 1. Two dogs 100 6 and 7 are adjustably mounted on the table 105

1 and engage two levers 8 and 9 for operating the pilot switch 5. The levers 8 and 9 are connected to the pilot switch by means of links 10. It is apparent that at the end 5 of the movement of the table 1 toward the right, as shown in the drawing, the dog 6 engages the lever 8 and moves the pilot switch in one direction. Such operation of the pilot switch changes the rotation of the 10 motor 3 to effect movement of the table in the opposite direction. When the table 10 is near the end of its movement towards the left as shown on the drawing, the dog 7 engages the lever 9 and moves the pilot switch 5 in an opposite direction. Such movement of the pilot switch again reverses the direction of rotation of the motor 3.

A cutting tool 10 is mounted on a cross rail 11 which in turn is supported on uprights 12. The movement of the cross rail on the upright 12 and also the movement of the cross head carrying the cutting tool 10 is effected by means of a motor 13. However, inasmuch as my invention is not directed to the mechanism for controlling such motor, a detailed description of such mechanism will be omitted. Reference may be had to the patent to Greenleaf and Keefer, 1,299,192 dated April 1, 1919, for a more 30 detailed description of the operation of a similar motor.

Referring to Fig. 7 of the drawing, the pilot switch 5 is shown controlling a switch mechanism which in turn operates the motor 3 in a forward and in a reversed direction. Moreover, the switch mechanism completes a dynamic braking circuit through the motor under certain conditions. The motor 3 comprises an armature 14, an interpole winding 15, a shunt field-magnet winding 16, and a series field-magnet winding 17. The pilot switch 5 comprises a contact segment 18 which is adapted to bridge a set of contact members 19 in one position of the switch 40 and to bridge a second set of contact members 20 in the opposite position of the switch. A contact segment 21 is provided for bridging a set of contact members 22 or the contact members 20 according to the position 45 of the switch.

The switch mechanism, which is controlled by the pilot switch 5, is shown in detail in Figs. 1 to 5 inclusive and comprises two main electro-magnets 23 and 24, two supplemental electro-magnets 25 and 26, and an accelerating electro-magnet 27. The two main electro-magnets 23 and 24 are very similar in construction and accordingly only a detail description will be given of the 55 electro-magnet 23. The accelerating electro-magnet is very similar in construction to the electro-magnet 23 and accordingly only the points of difference between the accelerating magnet and the electro-magnet 23 60 will be pointed out. The supplemental elec-

tro-magnets 25 and 26 are similar in construction and operation and accordingly only a description of the supplemental electro-magnet 25 will be given.

The electro-magnet 23 comprises a switch lever 28 which is pivoted intermediate its ends and which carries contact members 29 and 30 near the ends thereof. The movable contact members 29 and 30 cooperate with two stationary contact members 31 and 32. A main magnet 33 is provided for so moving the switch lever 28 as to effect engagement between the contact members 29 and 31.

The main electro-magnet 24 comprises a pivotally mounted switch lever 34 which is operated by a main magnet 35. Two contact members 36 and 37 which are mounted near the respective ends of the switch lever 34 and cooperate with two stationary contact members 38 and 39. The accelerating electro-magnet 27 comprises a pivotally mounted switch lever 40 which is operated by a main magnet 41. Two contact members 42 and 43 are mounted near the respective ends of the switch lever 40 and cooperate with two stationary contact members 44 and 45. The movable contact member 43 is insulated from the switch lever 40. The movable member 42 is preferably directly connected to the switch lever 40. Moreover, the contact members 29 and 30 are directly connected to the switch lever 28 and the contact members 36 and 37 are directly connected to the switch lever 34.

Referring particularly to Figs. 1 to 5 inclusive the main electro-magnets 23 and 24, the accelerating electro-magnet 27 and the supplemental electro-magnets 25 and 26 are mounted on a switch panel 46 which is composed of any suitable insulating material. The switch panel 46 is mounted on a base member 47. A hinged cover 48 of any suitable size is provided for enclosing the switch mechanism. Two shunt field rheostats 49 and 50 are preferably mounted on the base member 47 adjacent to the switch mechanism.

Referring particularly to Figs. 2 and 3, a bracket 51 is attached to the panel 46 by means of suitable bolts and serves as a support for the switch lever 28 and the magnet 33 of the main electro-magnet 23. The bracket 51 is provided with two projecting ears 52 which pivotally support the lever 28 by means of a pin 53. The main magnet 33 is supported on the bracket 51 by a suitable bolt 54 which extends through the core of the magnet. The movable contact member 29 is pivotally mounted near one end of the switch lever 28 and is pressed or forced outwardly by means of a spring member 55, as shown in Fig. 3 of the drawing. A suitable electric conductor 56 is connected to the contact member 29 and to the switch lever 28. A stop member 57 is provided for limit-

ing the outward movement of the contact member.

The stationary contact member 31 is mounted on a plug 58 which is attached to the panel 46 by means of any suitable bolt 59. A U-shaped clip 60, which is attached to the plug 58 by means of screws 61, serves as a support for two insulating plates 62. The plates 62 are attached to the clip 60 by means of a bolt 63. The plates 62 are thus located adjacent to the contact members 29 and 31, and protect the adjacent apparatus from any arcs that may be formed by such contact members. A pin 64 projects from the side of the switch lever 28, as shown in Fig. 1 of the drawing, and serves to operate an auxiliary switch 65 for a purpose to be hereinafter set forth. The pin 64 engages a spring-pressed plunger 66 which in turn 20 operates the switch 65. The movable contact member 30 is preferably mounted near the lower end of the lever 28 in the same manner as the contact member 29 is mounted near the upper end of such lever. The stationary contact member 32 is mounted on a block 67 which is attached to the panel 46 by means of a bolt 68. A flexible conductor 69 is attached to the lever 28 by means of a screw 70. In the above construction it is apparent the switch lever 28 is freely and independently detachable from the remainder of the mechanism to permit inspection or replacement of parts. The switch levers of the other electro-magnets are detachable in a like manner. The bracket 51 is provided with a projecting portion 71 which extends adjacent to the contact members 29 and 31. Such projecting portion 71 is included in the magnetic circuit of the supplemental magnet 25 for a purpose to be hereinafter set forth.

The supplemental electro-magnet 25 comprises a coil 72 which is mounted on a core member 73. The core member 73 is supported on two brackets 74 and 75 which in turn are detachably secured to the panel 46 in any convenient manner, as by means of the screw 76. The lower bracket 75 extends horizontally in the direction of the adjacent main electro-magnet 23 and serves as a stop member for the switch lever 28, as shown in Figs. 1 and 3 of the drawings. The upper supporting bracket 74 extends horizontally in both directions. The projecting portion 71 of the bracket 51 cooperates with the projection 74 to form an air gap including the contact members 29 and 31. Such air gap is included in the magnetic circuit of the supplemental electro-magnet 25 and permits the electro-magnet to operate as a blow-out magnet in extinguishing any arcs that may be formed by the contact members 29 and 31. Referring to Figs. 1, 3 and 5 of the drawings, it is apparent the magnetic circuit of the supplemental mag-

net 25 so operates on the switch lever 28 as to oppose the action of the main magnet 23 on the lever. Thus, the supplemental magnet 25 not only serves as a blow-out coil for the contact members 29 and 31 but also 70 serves as a means for returning the switch lever 28 to initial position upon deenergization of the main magnet 23. The supplemental magnet 25 not only operates as above set forth but also serves as a blow-out magnet 75 for the accelerating electro-magnet 27. The bracket 74 extends adjacent to the contact members 42 and 44 to form an air gap including such contact members. Although an extended air gap occurs at the lower part 80 of the accelerating electro-magnet and the supplemental electro-magnet, the coil of the supplemental magnet is of sufficient strength to produce a flux flow across the contact members 42 and 44 for blow-out purposes. The main electro-magnet 24 with one exception is, as heretofore set forth, similar in construction and operation to the main electro-magnet 23. The projecting portion 85 from the bracket which supports the switch lever is oppositely disposed in the main electro-magnet 23 to the position of such projecting portion in the main electro-magnet 24.

The contact members 44 and 42 of the accelerating electro-magnet 27 are mounted and operated in a manner similar to like contact members in the main electro-magnet 23. A detailed description of such contact members is deemed unnecessary. The movable contact member 43 is insulated from the switch lever 40 and is directly mounted on a plug 77 which is carried by two stud bolts 78. The bolts 78 extend into the switch lever 40 as shown in Fig. 4 of the drawing and are insulated from the plug 77 by means of insulating bushings 79. Insulating collars 80 are disposed at opposite ends of the plug 77 and a suitable detachable conductor 81 is provided for electrically connecting the plug 77 and the contact member 43 to a contact member 82.

The supplemental electro-magnet 25 not only serves to blow out the arcs formed by the contact members 29, 31, 42 and 44 and to return the switch lever 28 to initial position but also operates an interlock switch member 83. The switch member 83, when in a released position, bridges a pair of contact members 84 which are included in the circuit of the magnet 35. The supplemental electro-magnet 26 comprises a coil 85 which not only serves as a blow-out coil for the contact members 36 and 38 of the main electro-magnet 24 but also operates a switch member 86. The switch member 86, when in a released position, bridges two contact members 87 which are included in the circuit of the magnet 33. The supplemental electro-magnet also returns the lever 34 to

initial position. Referring to Fig. 7, a resistor 88 is provided for controlling the acceleration of the motor 3 and a resistor 89 is provided for choking the inductive discharges from the shunt field-magnet winding 16.

When the pilot switch 5 is moved at the end of the return stroke into position for the cutting stroke, the contact segment 21 of the switch bridges the contact members 22, thus preparing a circuit for operating the main electro-magnet 24. The circuit for operating the main electro-magnet 24 is traced from one conductor 90 of the supply circuit through the contact members 22, which are bridged by the contact segment 21, the magnet 35, contact members 34, which are bridged by the switch member 83, switch lever 28, contact members 30 and 32, coil 85 of the supplemental electro-magnet 26 and series field-magnet winding 17 to the other conductor 91 of the supply circuit. The main electro-magnet 24 is operated and the motor 3 is rotated in such direction as to effect a cutting stroke by the planer. The circuit completed through the motor 3 is traced from the supply conductor 90 through the contact members 38 and 36, switch lever 34, resistor 88, interpole winding 15, armature 14, switch lever 28, contact members 30 and 32, coil 85 of the supplemental electro-magnet 26 and the series field-magnet winding 17 to the supply conductor 91.

The coil or magnet 41 of the accelerating electro-magnet 27 is connected across the terminals of the armature 14 by means of the contact segment 18 which bridges the contact members 20. Accordingly when the motor develops a predetermined counter-electromotive force, the switch lever 40 of the accelerating electro-magnet 27 is operated to connect the contact members 42 and 44. Upon engagement between the contact members 42 and 44, the resistor 88 is short-circuited to accelerate the motor.

When the end of the cutting stroke is reached, the position of the pilot switch is reversed so that the contact segment 18 bridges the contact members 19 and the contact segment 21 bridges the contact members 20. In such position, of the pilot switch, the main electro-magnet 23 is operated to complete a circuit through the motor 3 for returning the planer table. During such operation, the accelerating switch is again operated to short-circuit the resistor 88. At the completion of either stroke when the main electro-magnet 23 or 24 is released, a dynamic-braking circuit is completed through the motor. The dynamic braking circuit is traced from switch lever 34 through the contact members 37 and 39, coils 72 and 85 of the supplemental electro-magnet 25 and 24, contact members 30 and 32, switch lever 28, armature 14, winding 15, and the resistor 88

to the switch lever 34. The control of the shunt field-magnet winding 16 by means of the contact members 43 and 45 and the switch 65 is completely set forth in my co-pending application of which this application is a division and a detailed description thereof in this application is deemed unnecessary.

From the above description, it is seen I have invented a simple and compact switch mechanism which serves not only to operate a motor in a forward and in a reverse direction but also to complete a dynamic-braking circuit through the motor upon completion of either planer stroke. The switch mechanism may be readily dismantled for replacing or repair of any part and the supplemental electro-magnets which are disposed adjacent the main electro-magnets serve to perform a number of functions. In brief, the supplemental electro-magnets operate as blow-out magnets to extinguish the arcs formed by the adjacent electro-magnets and return the switch levers of the main electro-magnets to initial position upon the deenergization of such electro-magnets. Moreover, the supplemental electro-magnets operate interlock switches which prevent the operation of either main electro-magnet when a dynamic-braking current is flowing. In this regard, it should be noted the switch members 86 and 83 which are operated by the supplemental electro-magnets 25 and 26 are included in the energizing circuit of the main electro-magnets and prevent the operation of either of such electro-magnets when a dynamic-braking current is flowing. It should also be noted that the energizing coil of either main electro-magnet is completed through the lower contact members controlled by the switch lever of the opposite main electro-magnet. Such interlocking means prevent the simultaneous operation of the two main electro-magnets.

Modifications in the mechanism and in the arrangement and location of parts may be made within the spirit and scope of my invention and such modifications are intended to be covered by the appended claims.

What I claim is:

1. In a switch mechanism, the combination comprising a switch lever pivoted intermediate its ends, a contact member mounted on each end of said lever, stationary contact members co-acting with said movable contact members, a main magnet for operating the switch lever to close one set of said contact members, and means comprising a supplemental magnet for opposing the action of the main magnet on said lever and for blowing out the arcs formed at certain of the contact members.

2. In a switch mechanism, the combination comprising a switch lever pivoted intermediate its ends, connected contact mem-

bers mounted on opposite ends of said lever, stationary contact members coacting with said movable contact members, a main magnet for operating the switch lever to close 5 one set of said contact members, and a supplemental magnet opposing the action of the main magnet on said lever, the magnetic circuit of said supplemental magnet having an air gap including one set of said contacts members for blowing out the arcs formed at such contact members.

3. In a switch mechanism, the combination comprising a switch lever pivoted between its ends, contacts carried by the lever 15 at the ends thereof, stationary contacts adapted to coact with the respective contacts on the lever, a main operating magnet for moving the lever in one direction, a supplemental magnet adjacent the lever and 20 arranged to act thereon in opposition to the main operating magnet, and means associated with the supplemental magnet and forming a magnetic gap at one pair of the aforesaid co-acting contact member.

25 4. In a switch mechanism, the combination comprising an insulated bracket, a switch lever independently pivoted between its ends on the bracket, contact members carried by the lever at the ends thereof, 30 stationary contact members adapted to coact with the respective contact members on the lever, a main operating magnet for moving the lever in one direction, a supplemental magnet adjacent the lever and arranged to act thereon in opposition to the main operating magnet, and means associated with the supplemental magnet and with the bracket and forming a magnetic gap at one pair of the aforesaid co-acting contact members.

35 5. In a switch mechanism for controlling and reversing electric motors, the combination of an insulated bracket, a switch lever independently pivoted between its ends on the bracket, contact members carried by the lever at the ends thereof, stationary contact members adapted to coact with the respective contact members on the lever, blocks supporting the several stationary 40 contact members, an operating magnet for moving the lever in one direction, a supplemental magnet adjacent the lever and arranged to act thereon in opposition to the main operating magnet, means associated with the supplemental magnet and with the bracket and forming a magnetic gap at one pair of the aforesaid co-acting contact members, and insulating plates at both sides of the gap carried by the supporting block 45 for the corresponding stationary contact member.

60 6. In a switch mechanism for controlling and reversing electric motors, the combination of two brackets insulated from each other, switch levers independently pivoted

between their ends on the respective brackets and readily removable therefrom, a third bracket between the first said brackets, a third lever on the third bracket, contact members carried by the levers at the respective ends thereof, stationary contact members insulated from the brackets and from each other and adapted to co-act with the respective contact members on the levers, main operating magnets for moving the 70 levers in one direction, two supplemental magnets respectively adjacent the first said levers and arranged to act thereon in the opposite direction from the main operating magnets and means associated with the supplemental magnets and with the first said brackets for forming magnetic gaps at the co-acting contact members at one end of each lever.

7. In a switch mechanism, the combination comprising two switch levers pivoted between their ends, contact members carried by the levers near the ends thereof, stationary contact members adapted to co-act with the respective contact members on the levers, a main operating magnet for each of said levers, a supplemental magnet located adjacent to each lever and arranged to act thereon in opposition to the associated main operating magnet, and an interlock switch 80 operated by each supplemental magnet and included in the circuit of the opposite main magnet.

8. In a switch mechanism, the combination comprising two switch levers pivoted between their ends, contact members carried by the levers near the ends thereof, stationary contact members adapted to co-act with the respective contact members on the levers, a main operating magnet for each of said levers, a supplemental magnet located adjacent to each lever and arranged to act thereon in opposition to the associated main operating magnet, and an interlock switch 90 operated by each supplemental magnet, the lower set of contact members operated by each switch lever and the associated interlock switch being connected in circuit with the opposite main magnet.

9. In a switch mechanism, the combination comprising two switch levers pivoted between their ends, contact members carried by the levers near the ends thereof, stationary contact members adapted to co-act with the respective contact members on the levers, a main operating magnet for each of said levers, a supplemental magnet located adjacent to each lever and acting in opposition to the main magnet, the magnetic circuit of each supplemental magnet being arranged to form an air gap including the upper set of contact members operated by the associated switch lever, and an interlock switch operated by each supplemental magnet, the lower set of contact members op- 115 120 125 130

erated by each switch lever and the associated interlock switch being connected in circuit with the opposite main magnet.

10. In a switch mechanism for controlling and reversing electric motors, the combination of two brackets insulated from each other, two switch levers independently pivoted between their ends on the respective brackets and readily removable therefrom, contact members carried by the levers at the respective ends thereof, each contact member being electrically connected with the body of the corresponding lever, stationary contact members insulated from the brackets and from each other and adapted to be engaged by the respective contact members on the levers, operating magnets for the levers, and readily detachable electrical connections extending to the levers, the mounting and connection for each lever being such that it can be freely and independently removed from the remainder of the mechanism.

11. In a switch mechanism for controlling and reversing electric motors, the combination of two brackets insulated from each other, two switch levers independently pivoted between their ends on the respective brackets and readily removable therefrom, contact members carried by the levers at the respective ends thereof, each contact member being electrically connected with the body of the corresponding lever, stationary contact members insulated from the brackets and from each other and adapted to be engaged by the respective contact members on the levers, operating magnets for the levers, readily detachable electrical connections extending to the levers, and a supplemental detachable electrical connection extending to the aforesaid insulated contact member on one of the levers, the mounting and connection for each lever being such that it can be freely and independently removed from the remainder of the mechanism.

the levers, operating magnets for the levers, mounted on the corresponding brackets, and readily detachable electrical connections extending to the levers, the mounting and connection for each lever being such that it can be freely and independently removed from the remainder of the mechanism. 40

12. In a switch mechanism for controlling and reversing electric motors, the combination of three brackets insulated from each other, three switch levers independently pivoted between their ends on the respective brackets and readily removable therefrom, contact members carried by the levers at the respective ends thereof, one contact being insulated from the body of the corresponding lever and each other contact member being electrically connected with the body of the corresponding lever, stationary contact members insulated from the brackets and from each other and adapted to be engaged by the respective contact members on the levers, operating magnets for the levers, readily detachable electrical 50 connections extending to the levers, and a supplemental detachable electrical connection extending to the aforesaid insulated contact member on one of the levers, the mounting and connection for each lever 55 being such that it can be freely and independently removed from the remainder of the mechanism.

In testimony whereof, I hereto affix my signature.

HAROLD L. BLOOD.
